ALBERT A. CRIQUI, OF BUFFALO, NEW YORK.

CENTRIFUGAL FAN.

1,161,926.

Specification of Letters Patent. Patented Nov. 30, 1915.

Application filed September 3, 1914. Serial No. 860,024.

To all whom it may concern:

Be it known that I, ALBERT A. CRIQUI, a citizen of the United States of America, and a resident of the city of Buffalo, county of Erie, and State of New York, have invented 5 certain new and useful Improvements in Centrifugal Fans, of which the following is a full, clear, and exact description.

My invention relates generally to a multiblade centrifugal fan of the type in which 10 a large number of blades are arranged in annular series around a central space, open at one side for the entrance of the air which is drawn in through the central opening and forced outwardly through the spaces between the blades by centrifugal force.

My invention relates particularly to improvements in the formation of the blades, which form part of the wheel of the centrifugal fan. As is well known to those skilled 20 in the art, fans of this type are generally constructed to deliver air under pressure at a comparatively slow speed of rotation. In places where direct-connected fans, of this 25 type, are installed and a low pressure of air is desired, it is necessary to run the fan wheel at a slow speed and a large frame motor is therefore required in order that a slow 30 speed of rotation may be obtained. This is because of the fact that in most fan constructions, inventors have sought to produce fans in which the velocity of the air leaving the wheel would be greater than the peripheral velocity of the wheel.

The general object of my invention has been, therefore, to provide a fan having a wheel with blades in which the velocity of the air leaving the wheel shall be less than the velocity of the periphery of the wheel, 40 thereby producing a low velocity pressure at a comparatively high speed of rotation. A snail-shaped casing is used in connection with the wheel, by means of which a portion of the velocity pressure of the air leaving 45 the wheel is converted into static pressure. And my wheel, in connection with its casing, will produce a lower static pressure than a wheel having forward, curved or straight 50 blades in connection with its casing, when both wheels are running at the same peripheral speed.

Another object has been to provide a fan wheel having blades so formed that the friction of the air passing through the blades 55 shall be greatly minimized and thus produce a fan having a maximum efficiency.

Another object has been to provide a blade which shall equalize the resultant static pressure of the discharge of the air along the entire length of the same, and also one which 60 shall pick up the air at a minimum loss by shock or impact with the entering air.

Another object has been to provide a blade the surfaces of which are developed from two cones, having their curved surfaces tangent to each other.

Each blade of my fan, as shown herein, has a forward curve at the heel and a backward curve at the tip. By reason of the backward curve at the tip the kinetic energy 70 of the air as it leaves the tip is reduced to a minimum, thereby producing a low velocity pressure which is far less than that produced by the forwardly curved or straight surfaced type of blade.

Throughout this description I use the term "air" as applied to my fan, but obviously the same may be used for gases or other fluids and it is not intended to restrict this application to the use of air.

In my application for Letters Patent on improvements in centrifugal fans, filed February 20, 1914, Serial No. 819,861, I have shown and described a structure similar, in some respects, to that herein shown and described.

In the drawings which show an embodiment of my invention like characters of reference indicate like parts throughout the several views, of which:

Figure 1 is a side elevation of the complete fan, with a portion of the casing thereof broken away, the wheel blades being indicated only in diagrammatic form. Fig. 2 is a sectional elevation of the same and is taken on line 2-2 of Fig. 1. Fig. 3 is an end elevation of a complete blade and shows diagrammatically the manner in which the blade is developed. In this figure the blade shown has its tip and heel non-coplanar with the axis of the wheel and the end of the tip farthest from the inlet precedes the end of the tip nearest to the inlet. Fig. 4 is an end elevation of a blade similar to that shown in Fig. 3 except that the end of the tip of the blade farthest from the inlet follows the end of the tip nearest the inlet. Fig. 5 is an end elevation of a blade similar to those shown in Figs. 3 and 4 and shows in a diagrammatic manner a means of ascertaining the pressures and velocities of the air at the heel and tip of the blade. Fig. 6 is an end

elevation of a modified form of blade for a wheel having a diameter substantially equal at each end. Fig. 7 is a side elevation of the blade shown in Fig. 6.

5 Referring to the drawings, 6 is the wheel of my fan which is carried by a shaft 7, rotatably mounted in suitable bearings 8. For convenience of illustration I have shown the shaft provided with a pulley 9 for driving the same but obviously an electric motor or any other suitable direct-connected or belted means, may be used to furnish motive power to the fan. The wheel 6 is inclosed within a snail-shaped casing 10, which is 10 provided with an inlet opening or eye 11 opposite to the inlet end of the wheel 6 and provided with an inlet cone 12, which directs the air from the exterior of the casing into the central opening of the wheel. The casing 10 is also provided with a tangential discharge opening 13.

The blades 14 of the wheel of my fan are secured laterally at one end to a disk 15, carried by hub 16 secured to the shaft 7. 25 An annular band or ring 17 is disposed at the inlet end of the wheel and the outer ends of the blades are secured thereto by suitable means. In the ordinary type of fan, as is well known, the tendency of the entering air is to rush to the end farthest from the entrance and to be discharged from that part of the wheel, thus making the discharge at the entrance end of the wheel comparatively light. In order to take care of this inequality of the discharge at the tip of the blade, I change the curvature of the blade along the tip and thus change the angle at which the air leaves the same.

30 The blades of my fan are each developed from two cones, having their curved surfaces tangent to each other, and is arranged so that the surface of each blade is presented to the air at the heel of the blade and the convex surface is presented to the air as it leaves the tip of the blade. Each of these 45 blades may have its tip and heel coplanar or non-coplanar with the axis of the wheel and may have the entrance end of its tip and heel precede or follow the disk end 50 thereof, as desired, to suit the different conditions.

The blades 14 of my fan are each developed from the two truncated cones A and B, which have their surfaces in contact 55 along a line composed of a series of points included in the circumference of each of said cones. It will thus be seen that the cones are so arranged with relation to each other that when the blade is wrapped around their surfaces, a smooth forward and backward 60 curve is produced.

In Fig. 3 the blade 18 has its tip 19 non-coplanar with the axis o of the wheel and with its end 19^a, which is farther from the axis in 65 a radial direction, preceded by the end 19^b,

which is nearer the axis in a radial direction. The heel 23 of this blade is non-coplanar with the axis o of the wheel and has its end 23^a, which is farther from the axis in a radial direction, preceded by the end 23^b, 70 which is nearer the axis in a radial direction.

The blade shown in Fig. 4 has its tip 21 non-coplanar with the axis o of the wheel and has its end 21^a, which is farther from the axis in a radial direction, preceded by 75 the end 21^b, which is nearer the axis in a radial direction. The heel 22 of this blade is non-coplanar with the axis of the wheel and has its end 22^a, which is farther from the axis in a radial direction, preceded by 80 the end 22^b, which is nearer the axis in a radial direction.

85 Referring now to Fig. 5, where the pressures and velocities are shown diagrammatically, 24 is the tip of the blade and 25 the heel thereof. The end 24^a of the tip, at the disk end of the wheel, is farther from the axis in a radial direction and the end 24^b of the tip at the entrance end of the wheel is nearer the axis. The broken line 24^a—C 90 represents the lineal velocity of the tip of the blade at the end 24^a. The line 24^a—D represents the tangential line of discharge of the air as it leaves the tip of the blade at the end 24^a of the tip of blade. The resultant velocity of the air as it leaves the tip of the blade at the end 24^a is indicated by the full line 24^a—E. The line 24^b—C and the line 24^b—D represent respectively, the lineal 95 velocity of the blade and the tangential discharge of the air as it leaves the tip of the blade at the end 24^b. The resultant velocity of the air as it leaves the tip of the blade at the end 24^b is indicated by the full line 100 24^b—E. 105

The end 25^a of the heel of the blade is at the entrance end of the blade and the end 25^b is at the disk end of the blade. The broken line 25^a—c represents the lineal velocity of the end 25^a at the heel of the blade 110 and the broken line 25^b—d represents the radial velocity of the air passing from the blade at the end 25^a. The resultant velocity of the blade at the end 25^a is indicated by the full line 25^a—e. The lineal velocity of 115 the blade at the end 25^b of the heel is indicated by the broken line 25^b—c and the radial velocity of the air passing through the blade at this end is indicated by the broken line 25^b—d. The resultant velocity of the 120 air at the end 25^b of the blade is represented by the full line 25^b—e.

As hereinbefore pointed out, I may change the curvature of the blade at the tip so as to equalize the discharge of the air along the 125 same. By reference to Fig. 5 it will be seen that the angle formed between the line 24^b—C, representing the lineal velocity of the end 24^b of the blade and the line 24^b—D representing the tangential line of air dis- 130

charge passing through the blade at that end is less than the angle formed between the lines 24^a—C and 24^a—D. The less the angle between the line representing the lineal velocity of the tip of the blade and the line representing the tangential discharge of the air from the blade the greater will be the resultant velocity of the air as it leaves the tip of the blade. Thus, it will be clearly seen that the resultant velocity represented by the line 24^b—E at the end of the tip, which is nearer the axis in a radial direction is substantially equal to the resultant velocity represented by the line 24^a—E at the 10 end of the tip, which is farther from the axis in a radial direction, thereby equalizing the discharge along the tip of the blade.

The blade 26 shown in Figs. 6 and 7 is for use on wheels where the entrance end is 20 substantially of the same diameter as the disk end. The blade is developed from the surfaces of two truncated cones and the tip 27 thereof lies in planes which are parallel and coplanar with the axis of the wheel. 25 The heel 28 is non-coplanar and has its entrance end 28^a preceded by its disk end 28^b. The curvature of the tip of this blade is changed so as to equalize the air discharge along its tip, as heretofore described with 30 reference to the blade shown in Fig. 5.

While I have shown and described my invention as applied to a fan having a single wheel and a single inlet opening, it is obvious that it may be applied to fans having a 35 double opening or to fans where two wheels are provided, each with an inlet opening. These and other modifications of the details herein shown and described may be made without departing from the spirit of my invention or the scope of the appended claims.

Having thus described my invention, what I claim is:

1. A centrifugal fan having a wheel provided with a plurality of blades, the surface of each of said blades being made from a portion of the surfaces of two cones, having their curved surfaces tangent to each other, and the external diameter at the disk end of said wheel being substantially the 45 same as that at the entrance end thereof.

2. A centrifugal fan having a wheel provided with a plurality of blades, the surface of each of said blades being made from a portion of the surfaces of two cones, having their curved surfaces tangent to each other, the tip of each blade being substantially coplanar with the axis of said wheel and the heel of each of said blades being non-co-

planar with the axis of said wheel, and the disk end of said wheel being substantially 60 the same in external diameter as that at the entrance end thereof.

3. A centrifugal fan having a wheel provided with a plurality of blades, the surface of each of said blades being made from a portion of the surfaces of two cones, having their curved surfaces tangent to each other, the tip of each blade being substantially coplanar with the axis of said wheel, and the disk end of said wheel being substantially 65 the same in external diameter as that at the entrance end thereof.

4. A centrifugal fan having a wheel provided with a plurality of blades, the surface of each of said blades being made from a portion of the surfaces of two cones, having their curved surfaces tangent to each other, the disk end of said wheel being substantially 70 the same in external diameter as that at the entrance end thereof, and the tip of each blade being so shaped that the angle formed between the line representing the lineal velocity of the tip of the blade and the line representing the tangential discharge of air from the blade increases from the 75 entrance end of the wheel toward the disk end thereof.

5. A centrifugal fan having a wheel provided with a plurality of blades, the surfaces of each of said blades being made from a portion of the surfaces of two cones, and the tip of each blade being so shaped that the angle formed between the line representing the lineal velocity of the tip of the blade and the line representing the tangential discharge of air from the blade increases from the 80 entrance end of said wheel toward the disk end thereof.

6. A centrifugal fan having a wheel provided with a plurality of blades, the surface of each of said blades being made from a portion of the surfaces of two cones, having their curved surfaces tangent to each other, the heel of each of said blades being non-coplanar with the axis of said wheel, 105 and the disk end of said wheel being substantially the same in external diameter as that of the entrance end thereof.

In testimony whereof, I have hereunto signed my name in the presence of the two 110 subscribed witnesses.

ALBERT A. CRIQUI.
